SPRAY DEVICE

Stanley Meyer, Queens, N. Y.

Application August 27, 1933, Serial No. 227,027

8 Claims. (Cl. 299—83)

This invention relates to spray devices used for spraying various types and kinds of fluids, and more particularly to devices of this kind which are so constructed as to provide a vapor discharge rather than a solid fluid discharge to adapt the device for the vapor spraying of fluids of various kinds and classes; and the object of the invention is to provide a spray device consisting of an elongated double walled tube, the walls of the tube being arranged in spaced relation to each other to form a discharge chamber with means involving a valve unit at one end of the cylinder controlling the feed of fluid to the discharge chamber and a nozzle communicating with the other end of said chamber for discharging the fluid or vapor therefrom; a further object being to provide a pump including a plunger rod for introducing fluid into the valve means and for discharging fluid from the lower end of the cylinder or said unit into the discharge passage and through said discharge nozzle, means being provided for normally retaining the plunger in a fully depressed position against the action of a spring employed for moving the plunger in one direction; a still further object being to provide means at the nozzle end of the cylinder for detachably supporting the pump in connection with a suitable fluid receptacle; a still further object being to provide a final closure cap adapted to be arranged over the last named means and the rod of said piston to retain the device in inoperative position against accidental displacement facilitating the convenient carrying of the complete container and pump without danger of discharge of the contents from the container; and with these and other objects in view the invention consists in a device of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional view through a pump and container showing a closure or seal cap in exploded relationship thereto and illustrating the piston or plunger in a partially depressed position.

Fig. 2 is a view similar to Fig. 1 on a reduced scale showing part of the structure in full lines

and illustrating a modified form of closure or seal cap in operative position.

Fig. 3 is a sectional view on the line 3—3 of Fig. 1 on an enlarged scale; and,

Fig. 4 is a view looking in the direction of the arrows 4 of Fig. 1.

To illustrate one method of carrying my invention into effect I have shown in the accompanying drawing at 5 a pump unit which is attachable and detachable with respect to a suitably constructed container or bottle 6; that is to say, the pump unit may be made to suit certain types and kinds of standard bottles, or in some cases, specially designed bottles may be provided and the unit 5 will be constructed to suit such special type of bottles.

The unit 5 consists basically of a cylinder portion 7, a valve portion 8, a mounting flange 9, a nozzle 10, a piston 11, a piston or plunger rod 12 and a closure or seal cap 13. These parts 20 may be assembled as a unit and as such attached and detached to a bottle or to the threaded neck or discharge end 14 thereof.

The cylinder portion 7 of the pump unit consists of an inner tube 15 and an outer tube 16. These tubes are so arranged and secured together as to form an annular discharge chamber 17 between the inner and outer tubes throughout the length thereof substantially in accordance with the teachings in my prior Patent #2,069,076. 30 (For purposes of the record, it is to be known that my name has been legally changed to Stanley Meyer.) The inner tube 15 is provided with a discharge passage 18 placing the chamber 19 of said inner tube in communication with the annular discharge 17; whereas the outer tube 16 is provided with two discharge ports 20 placing the passage 17 in communication with the discharge port 21 of the nozzle 10 through the medium of tangential passages 22 communicating with a relatively large chamber in the nozzle 10 around the discharge 21. This chamber is illustrated at 23 in Fig. 3 of the drawing.

The valve portion 8 is in the form of a unit consisting of an outer thimble-shaped part 24, the bottom wall of which is provided with an admission opening 25 and a small inverted thimble-shaped part 26, the top wall of which is provided with a small central discharge 27. The side walls of the outer part 24 project beyond the top wall of the part 26 and extend onto the cylinder portion 7 and is either firmly pressed thereon or may be soldered, welded or otherwise attached. This extending portion is illustrated at 28 in Fig. 1 of the drawing. The lower end of the 55

cylinder portion 7 seats upon the inner thimble 26 and holds the same in position.

Arranged within the chamber formed between the two thimble-shaped casings, is a valve disc 29 which may be composed of leather and which controls the port 25 and another porous disc 30 composed of such material as hard pressed felt. Disposed between the parts 29 and 30 is a resilient body 31 of loose felt or any other suitable material. The parts 30 and 31 are preferably composed of materials capable of being saturated by the fluid in the container 6. In some instances, I have found that sponge rubber, cotton, wick strands, or the like are suitable. However, in many types and kinds of fluids, the use of the felt members is desirable. The valve 29 including the members 30 and 31 are of sufficient small diameter to provide clearance around these members as is illustrated in Fig. 1 of the drawing.

Arranged in the chamber 19 of the cylinder portion 7 is the leather piston or plunger 11 mounted on the inner end of the plunger rod 12 in a more or less conventional manner as is indicated at 32. Seating upon the lower end of the end portion of the rod 12 is a spring retaining cap 33 forming a seat for one end of a coil spring 34, the other end of which seats upon the inner casing 26 or the top wall thereof. The spring 30 normally moves the plunger rod 12 in an upward direction, the upward movement being terminated by the inturned flange 35 on the top wall of the nozzle 10. The flange and top wall are recessed at one side as indicated at 36, Fig. 1, to permit a lock pin 37 on the rod 12 to pass into the chamber 19 and to seat on the flange 35 when the rod is rotated to retain the rod in a fully depressed position against the action of the spring 34 disposing the enlarged head or finger piece end 38 of the plunger adjacent the top of the nozzle 10 in the manner indicated in Fig. 2 of the drawing.

The lower end of the nozzle 10 is provided with an outwardly extending flange 39 which is engaged by the top wall 40 of the retaining sleeve or member 9. The sleeve is threaded as seen at 41 to engage the threaded neck 14 of the container 6 in securing the entire pump 5 upon the bottle. The flange 39 serves to force a gasket 50 42 upon the upper edge of the neck 14 to effect a seal between the parts as will be apparent. The nozzle 10 will have a press-fit or may be brazed, soldered, or welded to the upper unit of the cylinder portion 7 to constitute an integral part thereof. The mounting means as at 9 provides, as will be apparent, an adjustable mounting of the device in connection with the bottle 6 so as to direct the discharge 21 of the nozzle in any desired direction with respect to the circumferential or peripheral dimensions of the bottle.

The closure or retainer cap 13 as shown in Fig. 1, consists of a lower threaded sleeve portion 43 adapted to engage the threads 41 of the retaining sleeve 9. The cap has a reduced upwardly extending housing 44 for receiving the nozzle 5 and the plunger head 38. In Fig. 2 of the drawing, I have shown a slightly modified retainer cap 13a having a lower sleeve portion 43a and a reduced upwardly extending housing 44a. The sleeve 43 is provided with two or more inward projections 45 adapted to frictionally engage outwardly projecting members 46 on the threaded mounting flange 9a. This modified form of retainer cap is adapted to be more

quickly and easily removed as will be apparent. The cap 13, 13a is preferably knurled as seen at 47, 47a, to facilitate attachment and detachment thereof as will be apparent and is provided with a gasket 48, 48a, adapted to form a seal against the upper surface of the flange 39.

In connection with the valve portion or unit 8, I wish to point out at this time that as shown in the accompanying drawing and described, this unit is designed for pumps wherein it is desirable to provide an atomizer or fine vapor spray rather than a spray discharge of fluid. However, the density or other properties of the discharge may be governed by varying the type and kind of elements 30, 31, employed and also by modifying 15 the nozzle structure and principally the discharge port 21 thereof.

With a device of the character illustrated, it will be understood that in the upward stroke of the piston or plunger 11 by the action of the 20 spring 34, fluid will be drawn from the container 6 into the valve unit by the movement of the disc valve 29 into open position and the member 31 and 30 will become saturated. No fluid, or at least no appreciable amount of fluid, will enter 25 the chamber 19. However, on the downward stroke of the piston or plunger 11, which is operated by hand or the finger of a hand, the air under high pressure serves to draw fluid from the saturated bodies 30, 31, through the aperture 30 27 and discharge the same into the chamber 17 and thus out through the discharge 21 of the nozzle 10. In the initial operation of the device one or two strokes will probably be necessary to thoroughly saturate the pads or elements 30, 31. 35 In other words, the effect of my present construction is substantially the effect of a conventional atomizer. However, in certain operations of the pump with certain fluids, a vapor may be sprayed into the chamber 19 and then immediately discharged in the downward movement of the plunger, greater vaporization or atomization of the fluid taking place until finally discharged from the nozzle. In other instances, I have found that the downward pressure of 40 air upon the members 30, 31, will operate to force the small portions of the fluid into the chamber 19 and thus be discharged in the manner previously stated.

It will be understood that the members or elements 30, 31, operate as check valves which check direct flow of fluid into the chamber 19 in the upward stroke of the piston or plunger; and as above stated, by modifying the degree of checking properties of these elements, greater or less fluid transmission to the chamber 19 may be provided. For example, in such spraying devices as used in spraying window cleaning fluids upon the windshields of motor vehicles, a more fluid discharge is sometimes desirable; whereas in 45 spraying facial treatment fluids, perfumes, insecticides, and the like, a vapor spray is desirable.

By using a soft and highly resilient member 31, this member will have sufficient resilient properties to support the member 30 against the 50 top wall of the casing 26 so that the member 30 functions as a check valve, the fluids being necessarily drawn through this valve or the material therein for discharge from the spraying device. In some instances, however, the resilient 55 properties of the element 31 will permit the air pressure to lower the member or element 30 in the casing 26 so as to form a thin layer of fluid within the casing 26 directly beneath the aperture 21, or even to displace a small portion of 60 65 70 75 80 85 90 95 98 99 100

the fluid into the chamber 19. I have found it desirable for the successful use of the pump in the production of fine vapor sprays to arrange the port 18 closely adjacent the upper wall of the casing 26 so that a more or less direct discharge of the fluid or vapor is provided. It will of course be apparent that two or more of the discharges 18 may be employed in some types of pumps and the arrangement of these discharge ports may be modified in pumps designed for different functions.

It will also be apparent that the coupling means as at 9 may be modified to suit containers or receptacles of different kinds and classes and in some cases a pipe extension leading to the port 25 may be provided in longer bottles, vessels, or containers as is taught in the prior patent hereinbefore referred to.

Having fully described my invention, what I claim as new and desire to secure by Letters Patent, is:

1. A spray device of the class described comprising a pump unit consisting of a cylinder portion, a valve portion at one end of the cylinder portion, a nozzle at the other end of the cylinder portion, and a plunger in the cylinder tensionally operated in one direction and manually operated in the opposed direction, the cylinder portion comprising inner and outer tubes arranged in spaced relation to each other with a discharge passage formed therebetween extending throughout the length of said tubes, means at one end of the inner tube adjacent the valve portion for placing said passage in communication with the bore of said cylinder unit, said nozzle having a discharge, means in the outer tube for placing the upper end of said discharge passage in communication with the nozzle discharge, means for adjustably supporting the cylinder including the nozzle thereof in connection with a container, said valve portion comprising a casing having a valve controlling admission of fluid from the container into said casing, fluid absorbing means in the valve casing for supporting the fluid therein and forming means checking discharge of fluid from the casing into the bore of said cylinder, the valve casing having a passage placing the same in communication with said bore, said absorbing means controlling said last mentioned passage, said plunger including a rod protruding through the upper end of said nozzle, and means coupling the rod with the nozzle retaining the plunger in a depressed position.
2. A spray device of the class described comprising a pump unit consisting of a cylinder portion, a valve portion at one end of the cylinder portion, a nozzle at the other end of the cylinder portion, and a plunger in the cylinder tensionally operated in one direction and manually operated in the opposed direction, the cylinder portion comprising inner and outer tubes arranged in spaced relation to each other with a discharge passage formed therebetween extending throughout the length of said tube, means at one end of the inner tube adjacent the valve portion for placing said passage in communication with the bore of said cylinder unit, said nozzle having a discharge, means in the outer tube for placing the upper end of said discharge passage in communication with the nozzle discharge, means for adjustably supporting the cylinder including the nozzle thereof in connection with a container, said valve portion comprising a casing having a valve controlling admission of fluid from the container into said casing, fluid absorbing means in the valve casing for supporting the fluid therein and forming means checking discharge of fluid from the casing into the bore of said cylinder, the valve casing having a passage placing the same in communication with said bore, said absorbing means controlling said last mentioned passage, said plunger including a rod protruding through the upper end of said nozzle, and means coupling the rod with the nozzle retaining the plunger in a depressed position, and a sealing cap detachable with respect to said unit for enclosing and sealing the nozzle and plunger rod.
3. A spray device of the class described comprising a pump unit consisting of a cylinder portion, a valve portion at one end of the cylinder portion, a nozzle at the other end of the cylinder portion, and a plunger in the cylinder tensionally operated in one direction and manually operated in the opposed direction, the cylinder portion comprising inner and outer tubes arranged in spaced relation to each other with a discharge passage formed therebetween extending throughout the length of said tubes, means at one end of the inner tube adjacent the valve portion for placing said passage in communication with the bore of said cylinder unit, said nozzle having a discharge, means in the outer tube for placing the upper end of said discharge passage in communication with the nozzle discharge, means for adjustably supporting the cylinder including the nozzle thereof in connection with a container, said valve portion comprising a casing having a valve controlling admission of fluid from the container into said casing, fluid absorbing means in the valve casing for supporting the fluid therein and forming means checking discharge of fluid from the casing into the bore of said cylinder, the valve casing having a passage placing the same in communication with said bore, said absorbing means controlling said last mentioned passage, said plunger including a rod protruding through the upper end of said nozzle, and means coupling the rod with the nozzle retaining the plunger in a depressed position.
4. A spray device of the class described comprising a pump unit consisting of a cylinder portion, a valve portion at one end of the cylinder portion, a nozzle at the other end of the cylinder portion, and a plunger in the cylinder tensionally operated in one direction and manually operated in the opposed direction, the cylinder portion comprising inner and outer tubes arranged in spaced relation to each other with a discharge passage formed therebetween extending throughout the length of said tubes, means at one end of the inner tube adjacent the valve portion for placing said passage in communication with the bore of said cylinder unit, said nozzle having a discharge, means in the outer tube for placing the upper end of said discharge passage in communication with the nozzle discharge, means for adjustably supporting the cylinder including the nozzle thereof in connection with a container, said valve portion comprising a casing having a valve controlling admission of fluid from the container into said casing, fluid absorbing means in the valve casing for supporting the fluid therein and forming means checking discharge of fluid from the casing into the bore of said cylinder, the valve casing having a passage placing the same in communication with said bore, said absorbing means controlling said last mentioned passage, said plunger including a rod protruding through the upper end of said nozzle, and means coupling the rod with the nozzle retaining the plunger in a depressed position.
5. A fluid intake control unit for a pump cylinder of the character described, said unit comprising a casing having a fluid inlet port at one end wall and a discharge port at the opposite end.

- wall registering with said cylinder, a disc valve in said casing controlling the first named port, another disc valve arranged adjacent and controlling said discharge port, said last named valve being composed of material capable of being saturated by the fluid introduced into said casing, and an intermediate body of resilient absorbent properties supporting said valves in spaced relation to each other.
10. 6. In a spray device of the class described employing a pump cylinder, a fluid passage arranged outwardly of said cylinder and extending longitudinally thereof, the lower end of said passage communicating with said cylinder thereby providing for the flow of fluid through said passage, to a nozzle disposed on the upper end of said cylinder, a valve unit controlling admission of fluid into said cylinder for subsequent discharge therefrom through said passage, said unit having an intake valve, an exhaust port in spaced relation to said valve and registering with said cylinder, and means between the valve and port for absorbing fluid entering said valve unit and for retarding the feed of the fluid into the cylinder through said port.
15. 7. In a spray device of the class described employing a pump cylinder, a fluid passage arranged outwardly of said cylinder and extending longitudinally thereof, the lower end of said passage communicating with said cylinder thereby providing for the flow of fluid through said passage, to a nozzle disposed on the upper end of said cylinder, a valve unit controlling admission of fluid into said cylinder for subsequent discharge therefrom through said passage, said unit 20 having an intake valve, an exhaust port in spaced relation to said valve and registering with said cylinder, and means between the valve and port for absorbing fluid entering said valve unit and for retarding the feed of the fluid into the cylinder through said port, said last named means comprising a pair of felt pads, one composed of highly pressed material, the other of loose resilient material, and the latter being disposed between the first mentioned felt pad 25 and said valve.

of said cylinder, a valve unit controlling admission of fluid into said cylinder for subsequent discharge therefrom through said passage, said unit having an intake valve, an exhaust port in spaced relation to said valve and registering with said cylinder, and means between the valve and port for absorbing fluid entering said valve unit and for retarding the feed of the fluid into the cylinder through said port, said last named means comprising a felt pad.

8. In a spray device of the class described employing a pump cylinder, a fluid passage arranged outwardly of said cylinder and extending longitudinally thereof, the lower end of said passage communicating with said cylinder thereby providing for the flow of fluid through said passage, to a nozzle disposed on the upper end of said cylinder, a valve unit controlling admission of fluid into said cylinder for subsequent discharge therefrom through said passage, said unit 20 having an intake valve, an exhaust port in spaced relation to said valve and registering with said cylinder, and means between the valve and port for absorbing fluid entering said valve unit and for retarding the feed of the fluid into the cylinder through said port, said last named means comprising a pair of felt pads, one composed of highly pressed material, the other of loose resilient material, and the latter being disposed between the first mentioned felt pad 25 and said valve.

STANLEY MEYER.
